UNITED STATES PATENT OFFICE.

ARTHUR BRÉCHOT, OF PARIS, FRANCE, ASSIGNOR TO COMPAGNIE D'INCINERATION INDUSTRIELLE, OF PARIS, FRANCE.

REFUSE-DESTRUCTOR.

1,226,943.

Specification of Letters Patent. Patented May 22, 1917.

Application filed June 4, 1913. Serial No. 771,634.

To all whom it may concern:

Be it known that I, ARTHUR BRÉCHOT, a citizen of the Republic of France, residing in Paris, France, have invented certain new 5 and useful Improvements in Refuse-De-structors, of which the following is a speci-
fication.

The present invention has for an object to provide a furnace particularly designed 10 for the burning of clinker-forming mate-
rials, such, for instance, as refuse of vari-
ous kinds. It is well known that, in the
incineration of garbage and other refuse,
this fuel gives rise to a very considerable
15 mass of ashes and cinders accompanied with
the formation of clinkers. In the operation
of such a furnace, it is necessary to clean the
hearth quite frequently in order to get rid
of the refuse. This labor is very onerous
20 and dangerous to the operator as it has heretofore been accomplished with the present
form of flat grate reached by opening a
door to the hearth. The opening of the
hearth and the raking down of the ashes
25 and clinkers (otherwise called "incandescent
substances") and causing these to fall out
of the hearth, is quite apt to cause fire-box
flames which not only develop a consider-
able heat, rendering this labor very burden-
30 some, but also frequently burst forth and
injure the operator, who is thus constantly
exposed to great danger from this source.
Moreover, when these incandescent cinders
35 fall into the receptacle placed in front of
the furnace, they are apt to give off flame
and flashes, not only immediately after their
deposit therein, but while they are being
carried from the furnace.

The present improvement is designed to
40 remedy the inconveniences and dangers
above referred to and to avoid the cooling of
the hearth due to the entry of external air
during the operation of clearing off the
grates, thereby assuring perfect combustion
45 of the refuse and waste. The present im-
provement also provides a forced draft to
the fire box and also provides means for
cooling the fire-box by a draft of air, not
only during the normal operation of the fur-
50 nace, but also during the times that the
hearth is being dumped. Another object
of the invention is to provide the furnace

with rails and the hearth with wheels,
whereby the entire hearth, comprising the
fire-box, grate, etc., may be readily removed 55
from the furnace and an interchangeable
hearth immediately substituted therefor.

The description which will follow, ref-
erence being had to the annexed drawing
given by way of example, will clearly show 60
the nature and the advantages of this inven-
tion.

Figure 1 shows in longitudinal sectional
view a furnace embodying the improve-
ment of the present invention particularly 65
constructed for burning household refuse,
and provided with a dumping fire-box or
hearth.

Fig. 2 is a front elevation thereof.

Fig. 3 is a horizontal section taken on a 70
plane at about the line X—X of Fig. 1; and

Fig. 4 is a vertical section taken on a plane
at about the line Z—Z of Fig. 1.

The dumping demountable hearth illus-
trated herein by way of example is designed 75
to permit the easy and rapid emptying of
the ashes and clinker, and is shown located
in a masonry furnace. The hearth is shown
comprising a hearth-pan 32 provided with
curved walls and normally disposed in a 80
horizontal position. To the upper edge of
the hearth-pan there is shown fastened
a fire-box 33 of trapezoidal section. The
bottom of the fire-box is provided with a
grate 34. An ash-pan 55 is shown pivoted 85
at 56 to the lower portion of the hearth-
pan 32. The inner part of the ash-pan is
provided with cross-bars 54 which serve
to support the independent grate elements
34. An air chamber is provided between 90
the hearth-pan and the fire-box and be-
tween the grate and the ash-pan for the
purpose of cooling the clinker-forming ele-
ments of the fuel. The hearth is mounted
so that it may oscillate for the purpose of 95
dumping, and is shown provided at its re-
spective ends with trunnions 35, 36 carried
by the hearth-pan 32 and supported in suit-
able bearings shown in the form of boxes
72, 73 mounted on a car or carriage pref- 100
erably formed of ribbed iron and compris-
ing two side portions 37, 38 connected by a
front portion 39. The two side portions are
provided with wheels 40, 41 mounted upon

rails 42, 43 located at the respective sides of the hearth chamber of the furnace. In the illustration, the front portion 39 of the carriage is designed to form a panel of the outer wall of the furnace and is completed by jointed plates of cast iron 44 and a refractory lining 45.

When the hearth is placed in the furnace, the panel formed by the front part 39 of the carriage is connected on one side to the masonry by means of bolts 46 and the other side to boxes of cast iron 70, 71 integral with this masonry, in which boxes are received the side portions 37, 38 of the carriage. These boxes are cut out for allowing the passage of the trunnions 35 and 36 and their bearings 72 and 73. The influx of air for effecting the cooling and for supporting combustion takes place in the illustrated apparatus on one side only and by means of a bent tube 74 connecting a conduit 19 with the trunnion 35 which is hollow.

In order to completely insulate the hearth, the box 70 being open on its two sides for the passage of the trunnion 35 and its bearing 72, there is placed externally of this box a plate 52 suitably bolted in position.

The grate, in order to be easily replaced by another, is formed of independent elements 34 held in position between the lower portion of the fire-box 33 and the cross bars or ribs 54 integral with the ash-pan 55. The ash-pan 55 (see Fig. 4) is shown provided with a small door 57 situated at the end opposite the air inlet passage 74, 35. This door is normally held closed by a spring 58 and is opened by means of a rock shaft 59 and lever 60. The inrushing current of air under the grate is sufficiently strong to expel the ashes from the ash-pan through this door when the door is open.

In the installation illustrated, the rotation of the hearth is effected by means of a handle 61 mounted on a worm 62 meshing with a worm-wheel 63 keyed upon the trunnion 35. The rotation of the hearth by means of the worm 62 may be utilized by means of a chain 64 and wheels 65 for bringing about at the same time the opening of a door 66 which closes the lower portion of the furnace. This concurrent opening of the door with the rotation of the hearth is to allow the discharge of the cinders, etc., which are emptied from the hearth. When the incineration of a charge of refuse coming from the sole 20 of the furnace and filling the fire-box is ended, the handle 61 is turned in order to cause the fire-box to make a rotation of about 180° and thus free it of its ashes.

In order to completely replace a hearth which is damaged or to permit temporary repairs to a hearth when required, the operation is substantially as follows: The operator disconnects the tube 74 from the plate

52 and the operating devices 59 and 60 from the door of the ash-pit, then the worm 62 is disengaged, the worm being shown supported by means of movable bearings 67 and 68; the chain 64 is then disconnected and then the panel 39 is unbolted. The chain or cable is then connected to the ring 69 of the carriage and it is drawn out of the furnace. Another hearth brought up on the rails by some suitable means, as, for instance, a turn-table, can be immediately put in the place of the one removed. It will be seen that this work can be performed very rapidly and without necessitating any material interference with the running of the furnace.

Claims:

1. A hearth comprising a fire-box, and a grate carried thereby, a hearth-pan disposed outwardly of such fire-box and connected to the upper edge thereof, there being an air chamber between the fire-box and hearth-pan, trunnions for pivotally supporting said hearth, and means for supplying air to the said air chamber while the hearth is in its normal and in its dumped positions.

2. A hearth comprising a fire-box, and a grate carried thereby, a hearth-pan disposed outwardly of such fire-box and connected to the upper edge thereof, there being an air chamber between the fire-box and hearth-pan, trunnions for pivotally supporting said hearth, means for supplying air to the said air chamber while the hearth is in its normal and in its dumped positions, and mechanism for turning the hearth on its pivots for dumping the same.

3. A hearth comprising a fire-box, and a grate carried thereby, a hearth-pan disposed outwardly of such fire-box and connected to the upper edge thereof, there being an air chamber between the fire-box and hearth-pan, trunnions for pivotally supporting said hearth, and means for tilting the hearth for dumping the same, an ash-pit door and mechanism for operating the same controlled by the hearth tilting mechanism.

4. The combination with a furnace, provided with a hearth chamber and rails located upon the respective sides thereof, of a carriage having wheels adapted to run upon said rails, and a hearth pivotally mounted upon the carriage and disposed between the said wheels and constructed and adapted to be tilted upon the carriage while the carriage is in position in the hearth chamber.

5. The combination with a furnace, of a hearth comprising a fire-box, a grate carried thereby, a hearth pan surrounding the fire-box and grate, mechanism for mechanically dumping the hearth, and means for supplying a current of air to the outside of the fire-box while the grate is in its normal and in its dumped position.

6. A hearth comprising a fire-box, a grate carried thereby, a hearth pan surrounding

the fire-box and grate and affording an air chamber between said fire-box and hearth pan, means for pivotally supporting the said hearth, and means for supplying air to said 5 air chamber while the hearth is in its normal and in its dumped position.

In witness whereof, I have hereunto signed

my name in the presence of two subscribing witnesses.

ARTHUR BRÉCHOT.
